LACING PROBE

Alexander S. Antepenko, Berwyn, Ill.

Application August 2, 1945, Serial No. 608,422

3 Claims. (Cl. 223—105)

1

The present invention relates in general to lacing and has more particular reference to a lacing probe or bobbin device to aid in lacing or threading a support or fastening member through looped or channeled portions of an article or member to be mounted on the support member.

An important object of the present invention is to provide an improved inexpensive bobbin device or probe adapted for attachment on a support member, such as a curtain rod, to provide thereon a removable lacing nose whereby to facilitate application of the rod through a hem or other looped or channeled portions of the curtain provided for the reception of the rod.

Another important object is to facilitate the application of a support member, such as a curtain rod, through support loops of channel portions of an article, such as a curtain, to be attached on the support member, by providing a lacing bobbin or probe adapted for attachment, as at the end of the support member, while it is being laced into supporting position in the support portions of the article.

Another important object is to provide a lacing attachment comprising a tapered nose or guard portion and resilient fastening clips adapted for insertion, as in the hollow end of a curtain rod, to support the nose portion of the device, as at the end of the rod, in position to guard the same and prevent snagging the end of the rod when the same is laced into an object to be supported on the rod.

Another important object is to form the nose portion of moldable material whereby to render inexpensive the manufacture of the device by providing for the molding of the nose portion directly upon resilient mounting clip means; a further object being to form the mounting clip means of resilient wire material whereby the attachment may be fabricated, at minimum expense, as a wire bending and plastic molding operation.

The foregoing and numerous other important objects, advantages, and inherent functions of the invention will become apparent as the invention is more fully understood from the following description, which, taken in conjunction with the accompanying drawings, discloses a preferred embodiment of the invention.

Referring to the drawings:

Fig. 1 is a perspective view of a bobbin device embodying the present invention;

Fig. 2 is an elevation view showing the bobbin attached in operative position at the end of a hollow curtain rod;

Fig. 3 is an enlarged sectional view taken substantially along the line 3—3 in Fig. 2;

2

Fig. 4 is an enlarged perspective view of a clip forming a part of the device; and

Fig. 5 is a modified form of mounting clip.

To illustrate the invention, the drawings show 5 a bobbin attachment 11 adapted for connection, as at the end of a support member 12, such as a hollow curtain rod. The bobbin attachment comprises a nose portion 13 of ovoid sectional configuration and tapering from base to tip 10 whereby the portion 13 has a rear wall 14 and outwardly curved side walls 15 of generally shield-like marginal configuration, outwardly dished from their meeting edges 16.

Clip means 17 is secured to the nose portion 13 15 in position extending outwardly of the rear wall 14, said clip means 17 preferably comprising resilient prongs 18 adapted for removable attachment to the end of the member 12, as by pressing the prongs into resilient clamping engagement therewith. The rear wall 14 preferably has an area larger than the sectional area of the member 12 whereby, when the device 11 is in mounted position, said wall 14 may abut against, overlie and cover the end edges of the member 12 to form 25 an end guard and lacing nose facilitating the application of the member 12 endwise through restricted loops or channels formed on an article, such as a curtain, to be mounted on the member 12.

30 In this connection, the device 11 is adapted to cover the usually raw, cut end edges of the member 12 and prevent the same from snagging with, and injuring the material of the curtain or other article in which it may be desired to 35 insert the member 12. The smooth, tapering surfaces 15 and the rounded leading edge 16 of the nose portion 13 serve to guide the article being mounted onto the member 12, thereby facilitating and reducing the lacing operation to utmost simplicity.

As shown more particularly in Fig. 4 of the drawings, the prongs 18 may each comprise a strip of resilient material, such as wire, bent to provide a mounting stem 19 and resilient prong 45 portions 20, including a portion 21 forming an extension of the mounting stem, and a resilient bent leg portion 22, preferably inclined at an acute angle with respect to the extension 21, a continuation 23 of the acutely inclined portion 50 22, the terminal portions of said continuation portion 23 being looped, as at 24, around the stem 19, whereby the portions 22 and 23 are normally held in expanded position by the inherent resilience of the parts, such expanded 55 position being determined and limited by the engagement of the loop portion 24 with the stem 19.

The clip means 17 preferably comprises at least a pair of prongs 18 secured in the nose portion 13 with the stems extending outwardly of and at right angles with respect to the rear wall 14, the stems of the prongs being substantially parallel and the yielding prong portions 22 and 23 of the two prongs extending outwardly of their supporting stems in opposite directions. In mounting the bobbin attachment in the member 12, the prongs 18 are merely pressed into the end of the hollow member, the wedging action of the member on the acutely inclined prong portions 22 serving to facilitate the mounting operation by resiliently compressing the prong portions 22 and 23 inwardly toward the stem portions 19, so that the inherent resilience of said portions 22 and 23 exerted outwardly, within the hollow member 12, may frictionally secure the bobbin attachment in mounted position. The stems 19 of the prongs are desirably mounted in closely spaced relationship and it is desirable to mount the prongs in offset longitudinal relationship so that the looped portions 24 may clear each other when the prongs are compressed to a maximum extent, as when the device is mounted in a hollow member having a restricted prong receiving opening.

The device may be constructed by performing the nose portion or head 13, and then inserting the prongs 18 by driving the stems thereof into the head, or by otherwise suitably mounting the stems in the head. It is preferable, however, to form the head of suitable moldable plastic material in which case the head may be molded in place about the prong stems 19, thereby completing the fabrication of the device in a single molding operation. It is desirable, also, that the prong stems 19 be provided with means for anchoring the same, in the head 13, against relative turning and axial movement in the head. To this end, the stems may be provided with lateral notches or grooves 25, as indicated in Fig. 4, or they may be bent or otherwise shouldered to anchor the same in the material of the head, and the embedded ends of the stems also may be mitered, as at 26, by cutting the same diagonally with respect to the longitudinal axis.

As illustrated in Fig. 5, the embedded ends of the prongs 18 may be interconnected, as at 27, by making both prongs from an integral length of wire. In such case, the interconnected stems serve to anchor themselves firmly in the head by virtue of the embedded connecting portion 27.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A lacing device of the class described comprising a guiding head and mounting clip means on and extending from said head in position to removably attach said head as at the end of a channeled support member, whereby to facilitate the lacing of said support member, as through a restricted loop or channel, in an article to be lacingly connected therewith, said mounting clip means comprising a pair of spaced apart resilient members having stem portions mounted on and extending from said head in generally mu-

10
15

tually parallel relationship, each of said resilient members having an integral outwardly bent support engaging portion forming a loop with the stem portion, said bent portion being formed with a terminal loop embracing the stem portion adjacent said guiding head, whereby said terminal loop may slide on said stem in a direction laterally thereof and guide the movement of said support engaging portion with respect to said stem.

2. A lacing device of the class described comprising a guiding head and mounting clip means on and extending from said head in position to removably attach said head as at the end of a channeled support member, whereby to facilitate the lacing of said support member, as through a restricted loop or channel, in an article to be lacingly connected therewith, said mounting clip means comprising a length of resilient wire having bent medial portions secured to said head and a pair of spaced apart wire members having stem portions extending from said head in generally mutually parallel relationship, each of said wire members having an integral outwardly bent support engaging portion forming a loop with the stem portion, an integral bent portion forming a terminal loop on said support engaging portion in position embracing the stem portion adjacent said guiding head, whereby said elongated loop may slide on said stem in a direction laterally thereof and guide the movement of said support engaging portion with respect to said stem.

3. A lacing device of the class described comprising a guiding head and mounting clip means on and extending from said head in position to removably attach said head as at the end of a channeled support member having opposed inner walls, whereby to facilitate the lacing of said support member, as through a restricted loop or channel, in an article to be lacingly connected therewith, said mounting clip means comprising a pair of spaced apart wire members having stem portions mounted on and extending from said head in generally mutually parallel relationship, each of said wire members having an integral outwardly bent support engaging portion forming a loop with the stem portion, an elongated terminal loop on said support engaging portion in position embracing the stem portion adjacent said guiding head, said stem portions being adapted to flex mutually inwardly, upon insertion of said clip means in a channeled support whereby to resiliently urge said support engaging portion in position engaging the opposed inner walls of the support member throughout the length of said support engaging portions.
